US00D912282S

(12) **United States Design Patent** (10) **Patent No.:** **US D912,282 S**
(45) **Date of Patent:** **** Mar. 2, 2021**

(54) **STAND FOR ELECTRONIC COMMUNICATIONS DEVICE**

(71) Applicant: **SPIGEN KOREA CO., LTD.**, Seoul (KR)

(72) Inventor: **Dae-Young Kim**, Seoul (KR)

(73) Assignee: **SPIGEN KOREA CO., LTD.**, Seoul (KR)

(**) Term: **15 Years**

(21) Appl. No.: **29/700,225**

(22) Filed: **Jul. 31, 2019**

Related U.S. Application Data

(63) Continuation of application No. 29/545,824, filed on Nov. 16, 2015, now Pat. No. Des. 859,417.

(57) **CLAIM**

The ornamental design for a stand for electronic communications device, as shown and described.

DESCRIPTION

FIG. 1 is a front perspective view of a stand for electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front perspective view of the stand with the kickstand rotated;

FIG. 10 is a front perspective view of the stand with the kickstand in a closed position;

FIG. 11 is another front perspective view of the stand with the kickstand in a closed position;

FIG. 12 is a front perspective view of the stand illustrating the electronic device in broken lines; and,

FIG. 13 is a front perspective view of the stand with the kickstand in a closed position illustrating the electronic device in broken lines.

The broken lines depict environmental subject matter and portions of the stand for electronic communications device that form no part of the claimed design.

1 Claim, 13 Drawing Sheets
